UNITED STATES PATENT OFFICE.

EDWIN W. M. BAILEY, OF AMESBURY, MASSACHUSETTS.

WINDOW GUIDE.

Application filed December 8, 1924. Serial No. 754,515.

To all whom it may concern:

Be it known that I, EDWIN W. M. BAILEY, a citizen of the United States, and resident of Amesbury, in the county of Essex and 5 State of Massachusetts, have invented an Improvement in Window Guides, of which the following is a specification.

This invention relates to that class of guides for the window glass in automobiles 10 in which the guide is made entirely of metal, a guide of this character being disclosed in my prior Patent #1,374,629.

In the manufacture of automobile bodies of various makes it is customary to use what 15 is known as "mill run" glass, or glass which is not assorted as to thickness, and, therefore, varies substantially in this respect. It is desirable that the force of frictional engagement of the guides with the glass shall 20 be uniform under all conditions, and, as metal guides of the type above referred to are usually made uniformly, by a rolling process, so that the force of frictional engagement of a guide with the glass varies 25 according to the thickness of the glass, some means for compensating for the variations which occur when mill run glass is employed, is practically essential.

While I have disclosed such a means in 30 my pending application Serial No. 502,333 this means is open to the objection that adjustment cannot be made while the glass is in position, and the primary object of the present invention is to provide a form of 35 metal window guide in which the glass engaging means thereof may be adjusted while the glass is in position therein, so that the adjustment may be readily and accurately accomplished without removal of the glass 40 after it has been inserted.

Another object of the invention is to provide, in connection with said guide, an improved means for securing the edge cushion for the glass in position.

45 I accomplish these objects in the manner hereinafter described and as illustrated in the accompanying drawings in which:—

Fig. 1 is a side elevation, partly in central vertical section, of a window guide embodying my invention.

50 Fig. 2 is a transverse section thereof on an enlarged scale.

Fig. 3 is a perspective view thereof.

55 Fig. 4 is a detail sectional view at line *x*—*x* of Fig. 3, on an enlarged scale.

Fig. 5 is a similar view at line *y*—*y* of Fig. 3.

According to my invention the guide is formed from a strip of thin resilient metal bent to provide a base 1 and side guides 2 and 3, the side guide 2 being connected to the base portion by extending the base laterally to form a semi-cylindrically shaped portion 4, which projects beyond the side in the form of a bead. The base is also 60 extended laterally beyond the guide 3 and is bent semi-circularly to form a resilient portion 5, which is connected to said guide 3 by a reversely extending portion 6, which 65 normally extends divergently with relation to the base from said portion 5. The edge portions of the guides 2, 3 are each rolled inwardly to form rounded, or beaded edges 7 and 8, for direct engagement with the glass as disclosed in my said pending 70 application. An edge cushion is provided, which also consists of a strip of resilient sheet metal, the same being bent to provide a foot portion 9, which is located between the extension of base 1 and the inclined portion 6 and extends obliquely upward from the base to points in proximity to the opposite guide 2 and then is extended reversely, 75 to provide a glass engaging portion 10, which terminates adjacent the guide 3. A 80 yieldable arm is thus provided which extends laterally the entire length of the guide. The inclined portion 6 is provided with a series of holes 11, which may be formed at 85 any convenient time in the manufacturing operation, and to connect the base 1 and foot 9, tongues 12 and 13 are simultaneously punched out of said base and foot respectively opposite each hole 11 and then are 90 bent over flat on each other and on the foot 95 as shown in Figs. 4 and 5, so as to clinch these parts together.

The window casing or pillar 14 is provided with the usual groove or rabbet to receive the guide strip, and, where a metal 100 covering 15 is employed, it is shaped to provide a recess 16 in one side and at the bottom of the groove, which extends throughout the length thereof, and in which the bead 4 of the guide is located. A moulding 105 17 is provided to form the other side of the groove and is secured in position by screws 18. The moulding is provided with a rabbet or recess 19 at its inner front side which is adapted to receive the bead 5 and inclined 110

portion 6 of the guide. The relative formation of the molding and guide strip may be varied to secure different results. It may be such that when the side guides 2, 3, are 5 separated to their fullest extent by their normal spring action, they will be adapted to receive a sheet of glass of the greatest thickness which is likely to be inserted. To apply the desired frictional force thereto 10 under such conditions, when the molding 17 is secured in position the attaching screws are only turned in far enough to bring the bottom of its rabbeted portion 19 into engagement with the inclined portion 6 of 15 the guide strip. If, however, the normal separation of the guides is such that the force of frictional engagement with glass of the greatest thickness is less than that desired, then the molding will be forced 20 against the inclined portion 6 by forcing the screws 18 in to a greater extent, thereby causing the guide 3 to be swung inward, for example, from the dotted line to the full line position of Fig. 2, so that what may 25 be considered as the initial set of the guides will be changed. That is, the guides are adapted to yield to an extent from the position in which they are set to provide the desired force of frictional engagement and 30 allow for irregularities or variations in thickness of the glass which is inserted therein.

It will be apparent that with the above described arrangement the initial set of the 35 guides may be varied to correspond to all variations in thickness of the glass, so that under all conditions the force of frictional engagement of the guides with the glass will be practically uniform. Also that the adjustment of the initial set of the guides may 40 be accomplished after the glass has been placed in position between the guides, so that the desired adjustment may be much more quickly and accurately secured than if 45 it was necessary to remove the glass each time the guides were to be readjusted.

As the beads at each side of the guide strip are firmly engaged by portions of the casing or pillar, it will be apparent that the 50 strip will be securely held in position without the necessity of employing other securing means.

When the glass is in position between the guides, its edge will be engaged by the end portion 10 of the spring arm 9 which will provide an effective cushion therefor.

I claim:

1. A window glass guide consisting of a strip of resilient sheet metal bent to provide 55 a base and a pair of side guides projecting therefrom in position to engage opposite sides of the glass, said base having a lateral extension and a reversely extending connection between said extension and the inner 60 end of one of said guides, said connection

being yieldable towards said base and having an outer face arranged for clamping engagement to depress the same and vary the initial set of its guide.

2. A window glass guide consisting of a strip of resilient sheet metal bent to provide a base and a pair of side guides projecting therefrom in position to engage opposite sides of the glass, said base having a lateral extension and a reversely extending connection between said extension and the inner end of one of said guides, said connection being normally disposed in divergent relation with the base and being adapted for depression towards the same to vary the initial set of its guide. 70

3. A window glass guide consisting of a strip of resilient sheet metal bent to provide a base and a pair of side guides projecting therefrom in position to engage opposite sides of the glass, said base having a lateral extension and a reversely extending connection between said extension and the inner end of one of said guides, said connection being yieldably supported by said extension 80 at a distance therefrom to permit depression of said connection by engagement with the outer side thereof to vary the initial set of the guide which it supports. 85

4. A window glass guide consisting of a strip of resilient sheet metal bent to provide a base and a pair of side guides projecting therefrom in position to engage opposite sides of the glass, said base having a lateral extension and a reversely extending connection between said extension and the inner end of one of said guides, said connection being yieldably supported by said extension 90 at a distance therefrom to permit depression of said connection by engagement with the outer side thereof to vary the initial set of the guide which it supports. 95

metal strip having a base portion seated on the bottom of said groove and two side guides extending outwardly therefrom, said base being extended laterally beyond the 5 groove and having a reversely extended portion resiliently connected thereto and to the adjacent side guide, and a clamping strip having adjustable means engaging the casing for forcing the strip against said reversely 10 extended portion to vary the initial set of said side guide.

7. In combination with a window casing having a longitudinal groove and a lateral recess leading from one side thereof at its 15 bottom, a resilient sheet metal window guide

disposed in said groove and formed to provide a base and oppositely disposed side guides extending outwardly therefrom, said base being laterally and reversely extended at each side to connect the same to the adjacent side guide, one extended portion being disposed in said recess and the other having a yieldable connecting portion with the corresponding guide and a molding strip 20 engaged with said yieldable portion and adjustably connected to the casing to vary the 25 normal position of its guide.

In testimony whereof, I have signed my name to this specification.

EDWIN W. M. BAILEY.
